ROBERT H. MOORE

By his Attorney

Benjamin Johnson

UNITED STATES PATENT OFFICE

ROBERT H. MOORE, OF NEW YORK, N. Y.

BOOKMARK

Application filed May 21, 1929. Serial No. 364,898.

This invention relates to book marks, and particularly to the type which is interchangeable, as distinguished from book marks which are permanently attached to or form part of the book itself.

The principal object of the invention is to provide an efficient and improved interchangeable book mark, which will in no way interfere with the using, storage, or shelving 10 of the book, will in no way injure or mar the book or the furniture upon which the book may be placed, will properly adapt itself to the efficient marking of any part of the book, which will have means for identification of 15 the book mark or of the book with which it is used, and which will have means for cutting the pages of the book, particularly the pages of finely bound editions wherein some or all of the leaves are frequently left in uncut 20 state.

Other objects and advantages will herein-after appear.

In the accompanying drawings:—

Fig. 1 shows a front elevation of the book 25 mark.

Fig. 2 is a side elevation of the book mark shown in Fig. 1.

Figs. 3 and 4 show a front and side elevation, respectively, of a book mark which 30 is a modification of the invention.

Figs. 5 and 6 are respectively a front elevation and side elevation of a book mark of another modification of the invention.

Fig. 7 shows in perspective a rear view of 35 a book, and of the book mark shown in Fig. 1, as the latter appears when in operative condition in connection with the book.

Fig. 8 shows a cross-sectional elevation of 40 the book, and a side elevation of the book mark shown in Fig. 7.

Fig. 9 shows in perspective a rear view of a book, and of the book mark shown in Fig. 5, as the latter appears when in operative condition in connection with the book.

The book mark, Figs. 1, 2, comprises a ribbon or double-cord 1 which is tied to a holder 2 in the manner shown. Said holder consists of a single piece of sheet-material, such as sheet metal or any other substance suitable for this purpose, and this material is

bent or configurated to form an oblique triangular plate-portion 3 having an eye 4 to which the cord 1 is directly tied. From the plate-portion 3 extends downwardly the main body of material 5, which is preferably stamped out to form a pair of operating portions 6, 7, the portion 6 being formed as a tongue or blade and the portion 7 being stamped away from portion 6 and formed as a U-shaped band, with both of said portions converging toward each other into the common body of material 5. The portions 6, 7 are springy and normally diverge away from each other in the manner shown in Fig. 2, and may be brought or pressed together into the same plane in the position shown in Fig. 8.

When utilizing this book mark the holder 2 thereof is inserted between the back-binding 8 and the body of leaves 9 of the book 10, in the manner illustrated in Figs. 7, 8, and the cords 1 may be then utilized for book marking purposes in the usual manner. While the sheet material 5 is here shown as of substantial thickness for convenience 75 of illustration, the same may in actual practice be made of very thin, springy, and flexible sheet material, whereby when the book is utilized or in closed state the holder 2 will in no way interfere with the binding, and will in no way injure or mar any portion of the book or the furniture upon which it may be placed.

The inclination of the plate portion 3 maintains it below the edge 11 of the book cover 12, as shown in Fig. 8, thereby preventing any contact of this plate-portion with anything outside of the limits of the book covers. As the portions 6, 7 normally spring away from each other the holder 2 is thereby firmly maintained in its place within the binding by the portion 6 bearing or pressing against the body of leaves 9 and the portion 7 pressing against the back-binding 8. The oblique form of the plate portion 3 serves to limit the inward placement and downward position of the holder 2 within the binding.

Normally this device is utilized for the above described usual book-marking functions, in the position and manner illustrated in Figs. 7, 8, but in case the book user finds that some 100

of the leaves of the book are uncut, as occurs frequently and often unexpectedly, he withdraws the book mark and holder 2 from the book 10, and utilizing the tongue 6 as a blade 5 or cutter he grasps the plate-portions 3, 5 in the manner of a handle and proceeds to cut up the pages or leaves with the blade 6 conveniently and efficiently, after which he may reinsert the entire device between the back-binding and leaves of the book, as indicated in Figs. 7, 8. The holder 2 may be made of such material that its tongue or blade-portion 6 will also serve the purpose of an identification card which will be found convenient for 10 writing or printing thereon the name of the owner of the book-mark or of the book, or the name of the seller of the book, or any other desired information, as is illustrated in Fig. 1.

According to the modification shown in 20 Figs. 3, 4, the holder 2 is made out of two pieces of sheet material 6a, 7a, the portion 6a constituting the blade of leaf-cutting element corresponding to the portion 6 and the portion 7a corresponding to the portion 7 and 25 forming an integral part of the plate-portions 5, 3, and the portions 6a, 7a are hinged to each other by means of the staple or rivet 13. When utilized for book marking purposes this device is operated in a manner precisely similar to the device shown in Figs. 1, 2, but when 30 it is desired to cut the leaves of a book the blade portion 6a is turned about its pivot 13 to a position shown by the dot and dash lines, Fig. 3, and the portion 7a is then grasped as 35 a handle and the leaves are cut with the blade 6a in this manner.

In the modification shown in Figs. 5, 6, the entire holder 2 is made out of a single piece of sheet material, and comprises plate-portions 3, 5, a tongue portion 14 projecting downwardly from the latter and serving as a place for inscribing book-identification matter, and a pair of spring portions 15, 16 which normally are maintained away from each 40 other and from the portion 14. The spring portions 15, 16 lie in the same general plane as the portion 14 and may be sprung laterally toward the latter. When utilizing this book mark its holder 2 is inserted between 45 the back binding and leaves of the book, in the manner illustrated in Fig. 9. As its portions 15, 16 tend to spring laterally away from each other the holder 2 is thereby firmly maintained in its place within the binding.

50 Variations may be resorted to within the scope of the invention, and portions of the improvements may be used without others.

Having thus described my invention, I claim:

60 1. A book mark comprising a single piece of material adapted to be inserted between the back binding and leaves of a book, said material having a portion adapted for securing a marker cord thereto, said material 65 consisting of springy portions normally pro-

jecting away from each other, and one of said portions being adapted to press against the interior side of the back binding and the other against the leaves of the book.

2. A book mark comprising a single piece of material adapted to be inserted between the back binding and leaves of a book, said material having a portion adapted for securing a marker cord thereto, said material consisting of springy portions normally projecting away from each other, one of said portions being adapted to press against the interior side of the back binding and the other against the leaves of the book, and one of the said portions being flat and formed as a blade for leaf cutting purposes. 70

3. A book mark having a portion adapted for securing a marker cord thereto, a pair of springy portions normally projecting away from each other and adapted to be inserted between the back binding and leaves of a book, and one of said pair of portions being adapted to press against the interior side of the back binding and the other against the leaves of the book. 75

4. A book mark having a portion adapted for securing a marker cord thereto, a pair of springy portions normally projecting away from each other and adapted to be inserted between the back binding and leaves of a book, one of said pair of portions being adapted to press against the interior side of the back binding and the other against the leaves of the book, and one of the said pair of portions being flat and formed as a blade 80 for leaf cutting purposes. 90

5. A book mark having a portion adapted for securing a marker cord thereto, a pair of springy portions normally projecting away from each other and adapted to be inserted between the back binding and leaves of a book, one of said pair of portions being adapted to press against the back binding and the other against the leaves of the book, and one of said portions being formed as a 95 blade and adapted for leaf cutting purposes and being pivoted to said other portion. 100

6. A book mark comprising a single piece of material adapted to be inserted between the back binding and leaves of a book, said material having an integral portion adapted for securing a marker cord thereto, said material having an integral central portion adapted for identification purposes, and said material having integrally therewith a pair 115 of springy portions normally projecting laterally away from each other and from said central portion. 120

Signed at New York, in the county of New York, and State of New York, this 18th day 125 of May, A. D. 1929.

ROBERT H. MOORE.
